The United States of America.

To all to whom these Letters Patent shall come:

WHENAS Samuel M. Mazy, a citizen of the State of Massachusetts, in the United States, hath alledged that he has invented a new and useful improvement in gates, with doors, a novel form, peculiar with the application of heddles, which improvement has not been known or used before his application; has ~~made~~ such that he doth verily believe that he is the true inventor or discoverer of the said improvement; has paid into the Treasury of the United States, the sum of thirty dollars, delivered a receipt for the same, and presented a petition to the Secretary of State, signifying a desire of obtaining an exclusive property in the said improvement, and praying that a patent may be granted for that purpose: THESE ARE THEREFORE TO GRANT, according to law, to the said Samuel Mazy, his heirs, administrators, or assigns, for the term of fourteen years, from the ~~date of his application~~ the day of the present, March, 1803, to have and to hold the full and exclusive right and liberty of making, contructing, using, and vending to others to be used, the said improvement, a description whereof is given in the words of the said Samuel Mazy, as follows:

In Testimony whereof, I have caused these Letters to be made Patent, and the Seal of the United States to be hereunto affixed.

Done under my hand, at the City of Boston, in this second day of March, in the Year of our Lord, one thousand eight hundred and three, and of the Independence of the United States of America, the one hundred and nineteen.

THOMAS JEFFERSON

By the PRESIDENT,

JOHN MARSHALL Secretary of State.

City of Boston, Massachusetts. To wit:

I DO HEREBY CERTIFY, That the foregoing Letters Patent, were delivered to me, on the second day of March, 1803, in the year of our Lord one thousand eight hundred and three, to be executed; that I have examined the same, and find them conformable to law. And I do hereby cause the same to the Secretary of State, within five days from the date preceding, to be filed. On the second day of March, 1803, in the year aforesaid.

JOHN MARSHALL
Secretary of State

My wife often claimed to understand Chinese better than I did, having part of the time, returning a description of the words you and I taught her herself, in my experiments in drawing up a grammar of Chinese, and this was the result.
